US0D1057534S

(12) **United States Design Patent** (10) **Patent No.:** **US D1,057,534 S**
(45) **Date of Patent:** **** Jan. 14, 2025**

(54) **UNIVERSAL JOINT**

(71) Applicant: **Hong Ann Tool Industries Co., Ltd.**,
Taichung (TW)

(72) Inventor: **Cheng-Wei Su**, Taichung (TW)

(73) Assignee: **HONG ANN TOOL INDUSTRIES CO., LTD.**, Taichung (TW)

(**) Term: **15 Years**

(21) Appl. No.: **29/836,127**

(22) Filed: **Apr. 25, 2022**

(51) LOC (15) Cl. **08-05**

(52) U.S. Cl. **D8/25**
USPC ....

(58) **Field of Classification Search**

USPC **D8/25, 21, 24**
CPC **B25B 23/0014; B25B 23/0028; F16C
2361/41**

(57) **CLAIM**

The ornamental design for a universal joint as shown and described.

DESCRIPTION

FIG. 1 is a perspective view of a universal joint showing my new design;

FIG. 2 is a front view of the universal joint of FIG. 1;

FIG. 3 is a rear view of the universal joint of FIG. 1;

FIG. 4 is a left view of the universal joint of FIG. 1;

FIG. 5 is a right view of the universal joint of FIG. 1;

FIG. 6 is a top view of the universal joint of FIG. 1; and,

FIG. 7 is a bottom view of the universal joint of FIG. 1.

The dash-dash broken lines are included for the purpose of illustrating portions of the universal joint and form no part of the claimed design.

1 Claim, 7 Drawing Sheets
